UNITED STATES PATENT OFFICE

131,281

DESIGN FOR A COMBINED CAP AND CLIP FOR A MECHANICAL PENCIL OR SIMILAR ARTICLE

Hans A. Bauer, Chicago, Ill., assignor to Auto-point Company, Chicago, Ill., a corporation of Illinois

Application July 31, 1941, Serial No. 102,592

Term of patent 14 years

To all whom it may concern:

Be it known that I, Hans A. Bauer, a citizen of the United States, residing at Chicago, in the county of Cook and State of Illinois, have invented a new, original, and ornamental Design for a Combined Cap and Clip for a Mechanical Pencil or Similar Article, of which the following is a specification, reference being had to the accompanying drawing, forming a part thereof.

In the drawing:

Fig. 1 is a front elevation of a combined cap and clip for a mechanical pencil or similar article embodying my design.

Fig. 2 is a side elevation thereof.

Fig. 3 is a top plan view thereof.

I claim:

The ornamental design for a combined cap and clip for a mechanical pencil or similar article, substantially as shown.

HANS A. BAUER.
